[57] CLAIM

The ornamental design for wall paneling, as shown and described.

DESCRIPTION

FIG. 1 is a plan view of my invention, with the opposite side being of unornamented planar design;

FIG. 2 is a plan view showing an enlarged area of my invention to more clearly illustrate surface details thereof; and

FIG. 3 is an edge view taken along lines 3—3 of FIG. 1, showing the surface configuration of my invention.

*Fig. 1.**Fig. 2.**Fig. 3.*
